DEVICE FOR DEVELOPING PHOTO-
REPRODUCTIVE PAPERSLouis Veyret, Paris, France, assignor to La Cello-
phane, Paris, France, a French company

Application June 7, 1949, Serial No. 97,687

1 Claim. (Cl. 95—89)

1 Photoreproductive papers in which the sensitized coating consists of a stable mixture of a photosensitive diazo and an azo compound are usually developed by the mere action of ammonia gas. A large number of more or less complicated machines or devices have been conceived to accomplish this operation. A practical condition generally imposed upon such devices is the deodorization of the sheets after development, since the ammonia gas retained by them in the absence of such a supplementary operation will be diffused in the atmosphere of the room and render occupancy disagreeable.

The present invention relates to an improved device for developing photoreproductive papers, affording the deodorization of the said papers after development with ammonia gas by very simple means. This device, which has no damper or valve, its operation being effected entirely by a simple intermittent rotary motion of a moving part, is chiefly characterized in comprising a rotary drum divided into three longitudinal compartments and mounted in a fixed outer distributing drum in such a manner that each compartment in turn is successively placed in communication with the open air for insertion of work, with a source of ammonia for developing the work, and with a deodorization circuit.

Other characteristics will appear from a further description below.

In the accompanying drawings, intended by way of example only:

Fig. 1 is a longitudinal section taken on the line 1—1 of Fig. 2 of a machine pursuant to the invention;

Fig. 2 is a transverse section taken on the line 2—2 in Fig. 1;

Fig. 3 is a top plan view of the machine;

Fig. 4 is an end view thereof;

Fig. 5 is a transverse section similar to Fig. 4 showing a modification of the machine;

Fig. 6 is a longitudinal vertical section of another modification taken on the line 6—6 in Fig. 7;

Fig. 7 is a plan view of the machine shown in Fig. 6; and

Figs. 8 and 9 are horizontal sections taken on the lines 8—8 and 9—9, respectively, in Fig. 6.

In the example shown in Figs. 1 to 5, which relate to an apparatus with a horizontal axis, the said apparatus has a fixed outside drum T. This drum consists of a cylindrical wall 1 with horizontal axis X—X and two heads 2 and 3. The wall 1 is preferably fitted with a base 4 or other means of placing it on a table or other hori-

zontal support. This wall is open in its upper portion at 5 along a central angle x less than or at most equal to 120°. The head 2 is formed in one piece with, or may be attached to, the wall 1, and is cut out at 6 at the same central angle x, the cutout not reaching to the axis X—X. It may for example have the trapezoidal form shown in Fig. 4.

The other head 3 is circular. It is immovable and fixed to the wall 1 by suitable means, e. g. by means of screws not shown.

The cylindrical wall 1, near its two ends and along one generatrix, bears two holes 7 and 8 fitted with connections 9 and 10. More or less directly opposite, it has an additional elongated opening 11 which opens into a reservoir 12 tightly sealed to the said wall 1 by a flange 13 and screws 14 (Fig. 2).

The cylindrical drum T contains another drum T' inserted by removal of the detachable head 3. The drum T' may turn with light friction inside the drum T. It has a cylindrical wall 15 and a rear head 16 and is open at the other end. Its interior is divided into three compartments a, b, c (Fig. 2) with central angles of 120° by three radial partitions 17 attached to an axial hub 18.

Finally, the wall 15 of the drum T' is perforated at 19, into the various compartments a, b, c except on the small portions n, p (Fig. 2) corresponding to the partitions 17.

To facilitate rotation of the drum T', its hub is preferably prolonged forward by a shaft 23 passing through the front head of the drum T and fitted with a small operating knob 21.

The front edge 22 of the interior drum T' bears lightly against the inside surface of the wall 2 of the outside drum T, so as to afford a substantially tight seal between the two working compartments b and c. The tightness of the joint may moreover be increased by attaching strips of flexible material to the front edges of the partitions 17, or by lining the front head 2 of the fixed drum T with felt.

In using the apparatus, one of the connections 9, 10 communicates with the open air while the other is connected to the suction or exhaust of a fan. Finally, an ammoniacal solution is placed in the tank 12.

Then the operation will be as follows. Material to be developed is inserted at a through the opening 6. The material in C is in process of development. The material in b is in process of deodorization by the air current set up between the connections 9 and 10 by the fan communi-

cating with one of them. When developing is completed, the inside drum T' is turned through 120° in the direction of the arrow f (Fig. 3), so that the developed sheets that have been deodorized in b can be removed at a, while those just developed in c pass into the deodorization compartment b and those to be developed pass at c into the compartment filled with ammonia vapors.

It may be noted (Fig. 2) that the arc r, s, less than 180°, between the opening 11 where the ammonia vapors enter and the ventilating holes 7 and 8 is sufficiently great so that these openings cannot communicate simultaneously with the same compartment of the drum T', thus avoiding any needless loss of ammonia gas.

In the form shown in Fig. 5, the size of the perforated areas is reduced with a view to increasing the length n, p of the unperforated arcs, so that the ammonia reservoir will at no time discharge vapor to the outside. In fact, as soon as a partition 17a, in the course of the rotation of the drum T' in the direction of the arrow f, has arrived at the point of exposing the ammonia tank 12, the neighboring unperforated arc of the following partition 17b has already partially engaged the outer drum T at t.

In the same Fig. 5, the ventilating holes 7 and 8 are moreover so placed as not to open into a perforated portion of the movable drum until after the access opening for the ammonia vapors has been completely covered by the following unperforated arc.

Similar results could be obtained without restricting the perforated surface of the movable drum by reducing the angle x of aperture of the fixed drum, except that this angle must always remain sufficiently large to permit convenient loading and unloading of the device.

Figs. 6 to 9 show a modification of the device with a vertical axis.

The outer drum T has a cylindrical wall 23 with vertical axis Y—Y, rigidly and tightly fixed to a lower bottom 24 and a false bottom 25. A diametral partition 26 divides the space between these two heads into two chambers 27 and 28. The air chamber 27 opens to the outside through an opening 29 and also into the fixed drum through an opening 30 of the double bottom 25 (Fig. 9). The chamber 28, which is to receive the ammoniacal solution 31, opens into the drum T through an opening 32 in the false bottom 25. Finally, the fixed drum T is provided with a cover 33 (Figs. 6 and 7) with opening 34 for loading and opening 35 for connection to a fan.

The inside drum T' has an unbroken cylindrical wall, whereas its head 37 resting on the false bottom 25 is perforated at 38. Three vertical partitions 29 form three compartments a', b', c'.

In the position shown, the compartment a' is

in loading position, b' is the developing position and c' the deodorization position.

A knob 40 serves to revolve the drum T' in the direction of the arrow.

The compartment 28 may contain substances capable of absorbing ammonia gas, such as sulfuric acid or sodium bisulfate, thus accomplishing the deodorization within the apparatus itself without venting the ammonia gas released from the developed material to the outside.

It would also be possible, in that case, to eliminate the forced air current, since with the elimination of the upper exhaust opening 35, the ammonia released by the paper would pass through the opening 30 to be fixed by the absorbent substances.

An analogous arrangement could likewise be made in the horizontal devices of Figs. 1 to 4 and Fig. 5.

The invention is in no way restricted to the embodiments shown and described, these having been given solely by way of example.

What is claimed is:

A device for developing photoreproductive paper by the action of ammonia gas, comprising a stationary drum having an imperforate peripheral wall and a pair of end walls, an inner drum mounted to rotate therein, said inner drum having a cylindrical wall in sliding contact with said first cylindrical wall and having an open end, and having radial partitions forming three equal compartments, one of said end walls having an opening for the insertion of paper to be developed through the open end of said inner drum into a compartment thereof, an ammonia reservoir having a duct communicating through the peripheral wall of said stationary drum with said inner drum, an ammonia vent in the peripheral wall of said stationary drum, said duct, vent and opening being spaced to register respectively with the three separate compartments, said duct and vent being spaced a greater peripheral distance than the peripheral extent of each compartment, the peripheral wall of said inner drum being perforated and having sectors between compartments of an extent to completely close off said duct and said vent as said areas pass the same.
